CLAIM

The ornamental design for a skincare applicator, as shown and described.

DESCRIPTION

FIG. 1 is a front perspective view of a skincare applicator showing the new design;

FIG. 2 is a back perspective view thereof;

FIG. 3 is a front elevation view thereof;

FIG. 4 is a left side elevation view thereof;

FIG. 5 is a top plan view thereof;

FIG. 6 is a bottom plan view thereof;

FIG. 7 is a cross-sectional view thereof taken in the direction of line 7-7 in FIG. 6; and,

FIG. 8 is an exploded view of the skincare applicator.

The broken lines shown in the drawings depict portions of the skincare applicator that form no part of the claimed design.

1 Claim, 4 Drawing Sheets
